MEANS FOR VACUUM SEALING FLEXIBLE
PACKAGESSamuel H. Berch, Beverly Hills, Calif., assignor
to The Flexible Vacuum Container Corporation,
Los Angeles, Calif., a corporation of Nevada

Application January 22, 1944, Serial No. 519,372

1 Claim. (Cl. 93—6)

1

This invention relates to flexible package machinery, and particularly pertains to a means for vacuum sealing flexible packages.

The present application is a continuation in part of my co-pending application entitled "Vacuum packaging machine," Serial No. 450,297; filed by me in the United States Patent Office July 9, 1942, now Patent No. 2,428,192, issued September 30, 1947. This vacuum packaging machine is designed to handle flexible containers which are constructed with an inner liner, the faces of which unite to form a vacuum-tight seal under the action of heat and pressure. The machine is provided with a magazine carrying empty packages formed from a blank by making a reentrant fold therein, and which packages are held in the magazine in a flat condition and are automatically removed therefrom, shaped to form a container of final configuration and are then placed within individual carrying molds, in which molds they are successively carried to a filling station and to a final sealing station. The present invention is concerned with the construction and operation of the sealing apparatus at said final sealing station. In order to obtain volume production from the machine it is desirable to arrange the molds in groups extending transversely of the machine and to move a group of molds through the machine in step-by-step operation, and to simultaneously deposit the shaped containers within the molds, to thereafter fill the containers, and then vacuumize and seal the containers at the final sealing station. Since the containers are often filled with finely divided materials, and since there may be a slight variation in the thickness of the walls of the container at the point of forming the seam, it is necessary to provide means which will insure that the contents of the package will not be drawn between the abutting faces to be seamed, and to insure that proper pressure and heat shall be applied individually to the containers of a group at the final seaming station, whereby the individual sealed packages will each be vacuum-tight. It is the principal object of the present invention, therefore, to provide a method and apparatus for vacuum sealing packages, which includes a sealing head at which a group of individual flexible packages may be subjected to vacuum action without undue disturbance of the contents of the package, and to insure further that the mouth portion of the packages will be gripped, and that said packages are subjected to a vacuum action and then to pressure and heat in a manner to act upon each package individually, whereby a

2

uniform vacuum sealing action of each package will take place.

The present invention contemplates the provision of carrier units fitted with one or more mold pockets into which flexible containers are positioned, and which units may move to register with a vacuum head acting to subject the container and its contents to progressively increasing vacuum action, and to engage the mouth of the container in a manner to apply heat and pressure to the side walls thereof in forming a vacuum-tight seal between said walls and a durable, strong sealed seam, and means for progressively subjecting the packages to a suction action prior to sealing the packages under conditions of vacuum.

The invention is illustrated by way of example in the accompanying drawings in which:

20 Fig. 1 is a view in perspective showing the empty container with which the present invention is concerned.

Fig. 2 is a view in perspective showing the formed package ready for filling.

25 Fig. 3 is a view in perspective showing the finally filled and sealed package.

Fig. 4 is a view in side elevation showing the complete packaging machine and indicating the position of the sealing head.

30 Fig. 5 is an enlarged view in transverse section showing the sealing head, with parts broken away for sake of convenience.

Fig. 6 is a view in plan showing the sealing head and the relationship of the operating cylinders.

35 Fig. 7 is an enlarged fragmentary view in section and elevation showing the operating members of one of the sealing head units.

Fig. 8 is a view in central vertical section through the sealing head structure as seen on the line 8—8 of Fig. 7 and indicates the relationship of the parts of the sealing head structure prior to a sealing operation.

40 Fig. 9 is a view in central vertical section similar to Fig. 8 showing the parts of the sealing head in operation.

Fig. 10 is a fragmentary view in plan with parts in section as seen generally on the line 10—10 of Fig. 7 and shows the operating mechanism for 45 the sealing blades.

Fig. 11 is a view in vertical section and elevation as seen on the line 11—11 of Fig. 10 showing the mechanism for folding the blades into and out of sealing position.

50 Fig. 12 is a view in transverse section through

the low stage suction valve, as seen on the line 12—12 of Fig. 5.

Fig. 13 is a view in central vertical section through the high stage suction valve, as seen on the line 13—13 of Fig. 5.

Fig. 14 is a view in central vertical section through the exhaust valve, as seen on the line 14—14 of Fig. 5.

Referring more particularly to the drawings, 10 indicates a flexible package with which the present invention is concerned. This package is here shown as being made of sheet material folded upon itself to form front and back wall sections 11 and 12. The inner face of the sheet of material carries a lamina which may be of thermoplastic material or other suitable flexible material, preferably having qualities which insure that it will not transmit oxygen when a collapsible package made therefrom is sealed in vacuum and its walls are subjected to exterior atmospheric pressure. Such material should also have the characteristic that when heat and pressure are applied to abutting sheets thereof they will be united to form a vacuum-tight seam. Such seams are indicated at 13 and 14 in Fig. 1 of the drawing. It is to be understood that due to the construction of the sheet material forming the package the walls of the package are impervious to air, other gases, and moisture. The container formed as shown in Fig. 1 of the drawings, is to be shaped, filled with a commodity, and then vacuum sealed by the apparatus with which the present invention is concerned.

The machine for handling the container 10 and with which the present invention is concerned is generally indicated in Fig. 4 of the drawings. Here it will be seen that a base 15 is provided, at one end of which is a magazine station A including a magazine structure 16 within which the containers 10 are stored and from which they may be drawn by the mechanism associated therewith. Adjacent to the magazine structure is a filling unit B. This includes a hopper 17 and filling spouts 18. Adjacent to the filling station B is a package spreading and creasing station C, and beyond this station is the sealing station D, with which the present invention is particularly concerned.

The base structure 15 houses parallel horizontal shafts 19 and 20. The shaft 19 carries sprockets 21 and the shaft 20 carries sprockets 22. Around these sprockets are led conveyor chains 23 and secured transversely of the conveyor chains and arranged at spaced intervals therealong are mold units 24. These units carry a plurality of molds 25, as particularly indicated in Fig. 5 of the drawings, each of the molds being intended to receive one of the containers 10 after it has been shaped to assume the configuration shown in Fig. 2 of the drawings. When in this shape it will be noted that the seams 13 and 14 extend longitudinally of the narrow sides 26 and 27 of the container, and that relatively wide sides 28 and 29 are provided. The container when shaped and deposited into the pocket of a mold 25 has a square closed end, while the depth of the mold is such as to insure that the walls forming the open mouth of the container will project above the top of the molds, as particularly disclosed in Figs. 8 and 9 of the drawings.

The mold units 24 comprise a plurality of the molds 25 and these molds are disposed at right angles to the path of travel of the chains 23 upon which they are carried. The conveyor chains thus move the molds successively from the

magazine station A to the filling station B and then to the spreading and creasing station C and the sealing station D. The intermittent drive mechanism for the sprockets 22 and 23 will not be described, although it is understood that power is applied to main drive shaft 30 and that suitable intermittent driving mechanism transmits driving force to the shaft 20 carrying the sprockets 22. The details of construction of the apparatus shown at stations A, B and C are of no concern to the present case, and attention will therefore be directed to the construction of the sealing station D shown particularly in Figs. 5 to 11 of the drawings.

Referring particularly to Fig. 5, it will be seen that a mold unit 24 consists of a plurality of molds 25 which are spaced from each other along a plate 31. The plate 31 is secured to the sprocket chains 23 by fastening means 32. Supporting rails 33 are disposed beneath the plate 31 and are spaced longitudinally thereof to maintain the plate in a rigid horizontal position during the sealing operation. Mounted upon the upper faces of the sides of the base 15 are vertical standards 34. These standards consist of a block 35 secured to the base 15 by cap screws 36. The block 35 supports a vertical cylindrical shaft 37 upon which a sealing head 38 reciprocates vertically. The sealing head 38, as particularly shown in Figs. 8 and 9, includes a top plate 39, opposite side plates 40 and 41, and end plates 42. These form an inverted trough-like structure which may be lowered on the standards 34 to a position to form a sealed space over the mouth of the molds 25 in a mold unit registering with the sealing station. The lower edges of the side plates 40 and 41 and the end plates 42 are formed with channels 43 which are grooved to receive a packing strip 44. The packing strip 44 is intended to move into positive contact with the upper face of the plate 31 of a mold unit. This packing strip may be made of "neoprene" or other suitable deformable material which will form an air-tight seal between the plate 31 and the edges of the head structure 38.

The sealing head 38 reciprocates vertically upon the standards 34 as moved by pitman rods 45. The upper ends of these rods are pivotally connected to the sealing head by pins 46. The lower ends of the rods are pivotally connected by pins 47 to oscillating levers 48 mounted upon a pivot shaft 49. The oscillating levers 48 each carry cam rollers 51 at a point intermediate their ends. These rollers rest upon an eccentric cam 52 mounted upon a shaft 53. The shaft carries a gear 54 in mesh with a gear 55. This gear is mounted upon a shaft 56 which also carries a gear 57. The gear 57 is in mesh with a pinion 58 mounted upon the drive shaft 30. It is to be understood that the intermittent drive of the sprocket chains 23 is such that when a mold unit 24 is in register with the sealing station D and is disposed directly beneath the sealing head 38 the drive chain and the mold units will stand stationary while the sealing head goes through a cycle of operation to be lowered onto a mold unit and to be lifted therefrom.

Mounted upon the top plate 39 of the head 38 is a plurality of vertical brackets 59. These brackets are formed by parallel arms 60 and 61 which are integral with a base plate 62 and are secured by suitable fastening means 63 to the plate 39. Carried at the upper ends of the brackets are cylinders 64. These cylinders are open at their lower ends and are threaded at their

upper ends to receive a cylinder head 65. The cylinder heads 65 are each formed with a central threaded opening 66 to receive an extension of a manifold pipe 67. This pipe is fitted at one end with a flexible connection 68 leading to a source of air under pressure not shown in the drawings. Reciprocably mounted within the cylinder 64 is a piston 69 carried upon a piston rod 70. The piston rod 70 extends downwardly through a guide bore 71 in the base 62 of the bracket 59 and projects into the sealing head structure 38. Suitable packing 72 is disposed around the piston rod to prevent a leakage of air into or from the sealing head. Mounted upon the piston rods 70 and extending between the arms 60 and 61 of the bracket 59 is a cross-head 73, at the opposite ends of which springs 74 are secured. The upper ends of these springs are secured to a cross-head 75 mounted upon the top of each of the cylinder heads 65. It is intended that the delivery of air under pressure to the cylinders through the manifold 67 will cause the pistons 69 in all of the cylinders 64 to move down simultaneously, and when pressure is relieved for the springs 74 to retract the pistons upwardly within the cylinders. A suitable timing valve 76 is interposed between the source of fluid under pressure and the connection 68 so that the piston 69 will be reciprocated only when the sealing head and a mold unit are in proper registered position with each other, as shown in Figs. 8 and 9 of the drawings.

Also mounted upon the top plate 39 of the sealing head 38 are valve structures 77, 78 and 79. These are shown particularly in Figs. 12, 13 and 14, respectively. These valves are provided to carry out the vacuum sealing operation of the machine in accordance with the method set forth in U. S. Letters Patent No. 2,241,943 and issued to me May 13, 1941. In this patent it was explained that prior to the sealing of a package of the type here indicated by the numeral 10 the open package was subjected to suction action, whereby a vacuum would be created within the molds 25 of a mold unit 24 and within the sealing head 38, and that thereafter the package would be sealed. When this operation is completed according to the invention of the aforementioned patent the interior of the sealing head 38 and the molds of the mold unit are disconnected from the suction pump and a connection to the atmosphere is made, whereby the interior of the structure will be subjected to atmospheric pressure and the individual packages will be compacted and shaped to conform to the mold, as indicated in Fig. 3 of the drawings.

In view of the fact that the containers 10 are used to a great extent in packaging finely divided materials, such as coffee, milk, and the like, it has been found that if the contents of the package are subjected to a violent suction action the lighter material in the package is liable to be lifted from the mass and drawn between the abutting faces which are to comprise the sealed area of the mouth of the finished container. For that reason it is desirable first to subject the contents within the package to a relatively low degree of suction and to thereafter subject it to increased suction, so that a high vacuum will be attained without disturbing the contents of the package violently. In order to accomplish this result a low suction action is applied to the sealing head 38 while the valve 77 is open and the valves 78 and 79 are closed, after which the valve 77 is closed and the valve 78 is

opened. The valve 78 causes the high degree of vacuum to be created within the sealing head and the mold unit. When the desired period of suction action has been concluded the valves 77 and 78 are both placed in a closed position and the valve 79 is opened. This establishes communication between the sealing head and the atmosphere. In order to accomplish this action of the valves in synchronism a cam shaft 80 is mounted in suitable bearings 81 and driven through a flexible drive 82 from timing gears, whereby the valves 77, 78 and 79 will operate in sequence. The valve 77 is fitted with a bracket 83 which carries a pivot 84 upon which a rocker arm 85 is pivotally mounted. The lower end of this arm rides over a cam 86 upon the shaft 80 and the upper end of the arm bears against a valve plunger 87 by which the valve 77 is opened. Suitable spring means forming a part of the valve structure restore the plunger 87 to its original position and close the valve. The valve structure 78 includes a bracket 88 carrying a pivot pin 89 upon which a rocker arm 90 is pivotally mounted. The lower end of this arm rides over a cam 91. The upper end of the arm bears against a valve plunger 92 by which the valve 78 may be opened, it being understood that suitable means within the valve structure closes the valve and restores the plunger 92 to its original position. The valve 79 includes a bracket 93 carrying a pivot pin 94 upon which a rocker arm 95 is pivotally mounted. The lower end of this rocker arm bears against a cam 96 carried upon the cam shaft 80. The upper end of the arm bears against a valve plunger 97 by which the valve 79 may be opened, after which it is closed by suitable spring means within the valve structure. It will be understood that the valves 77, 78 and 79 open and close in sequence.

Mounted within the sealing head 38 are separate units for folding and sealing the mouths of the individual filled packages after they have been vacuumized. Attention is directed to the fact that while the pistons 69 and their rods 70 are simultaneously moved by action of the air under pressure delivered through the manifold 67, and that these rods operate various folding and sealing mechanisms, it is desirable that each of the folding and sealing mechanisms shall adapt itself to the individual package upon which it acts without reference to the other packages being folded and sealed, thus insuring that each package will be properly folded and sealed regardless of variation in its wall thickness. This structure is particularly shown in Figs. 7 to 11 of the drawings.

By reference to Figs. 8 and 9 of the drawings it will be seen that the individual molds 25 project a distance above the upper surface of the mold plate 31 and thus beyond the lower edges of the walls of the sealing head 38. Mounted within the sealing head, to be disposed upon opposite sides of the upwardly projecting portion of the molds 25 when the head is in its lowermost position, are folding and sealing arms 98 and 99. These arms are carried upon parallel shafts 100 and 101 which extend longitudinally of the sealing head and are supported at intervals along the length of the sealing head by bearing brackets 102. The shafts 100 and 101 are disposed in a horizontal plane parallel to the plane of the lower edge of the sealing head 38 and spaced a desired distance thereabove, although positioned to occupy a plane lower than that of the upper edge of the molds 25 when the

sealing head is in position over the molds. The arm 99 is intended to fold down over the top of a mold 25 and to engage the upwardly projecting portion 10a of the container 10 to fold the upwardly projecting portion of the side wall of the package downwardly and at right angles to the filled portion of the package. The filled level of material within the package occupies substantially the same plane as the plane of the upper lip of a mold. The arm 99 includes a flat blade 103 which is formed integral with supporting portions 104 disposed at right angles to the plane of the blade. The supporting portions terminate in bosses 105 disposed adjacent to opposite ends of the blade 103 and through which shaft 101 extends. Attention is directed to the fact that shafts 101 are provided, one for each of the molds 25, and that while the ends of the shaft are supported in the bearing brackets 102 with the shafts in longitudinal alignment, the shafts are individually rotatable. The free end of the folding blade 103 is offset and has a relatively thin end portion forming a face 106 and a shoulder 107. The end of the blade 99 is of a length to terminate along the vertical median line of the filled package 10 within a mold 25.

The folding arm 98 is formed with portions 108 connected to bosses 109 through which shafts 100 extend. The portions 108 are formed with blades 110. The free end of the blade 110 has an enlarged portion forming an inclined seat for a sealing pad 111. This pad is preferably made of rubber and extends longitudinally of the blade to form a face against which the sealing operation takes place. The enlarged end of the blade 110 has an offset portion 112 which overlies the narrow extension at the end of blade 103 when the blades 103 and 110 assume a position in substantially the same horizontal plane over the end of a complementary mold 25.

The shafts 100 and 101 carry gear segments 113 and 114, respectively. These segments are in mesh with gears 115 and 116, respectively, which are carried upon shafts 117 and 118, respectively, secured to the brackets 102. The gears 115 and 116 are in constant mesh, and as shown in Fig. 11 of the drawings the gear 115 is fitted with a crank pin 119 receiving a shackle 120. The opposite end of the shackle 120 is pivotally connected to a lever arm 121 by a pin 122. The lever arm is mounted upon a shaft 123. This shaft carries a radially extending screw 124 which projects through a circumferentially extending slot 125 in the boss of the lever 121. Due to this arrangement the shaft 123 will have limited rotation with relation to the lever arm 121, as represented by the space between end shoulders 126 and 127 of the slot 125. The shaft 123 is journaled within contiguous brackets 102 of the sealing head and is disposed within a plane above the shafts 117 and 118 and offset from the central median line of the sealing head. The shaft 123 also supports a sealing bar structure 128. This structure is formed with a base plate 129 carrying arms 130. The arms 130 are formed with bosses 131 through which the shaft 123 extends. Set screws are provided to secure the arms against rotation on the shaft. A pressure bar 133 is secured to the face of the portion 129 and is formed to receive an electric heating element 134. A pressure face 135 is formed on the bar 133 so that when the bar is swung downwardly in a sealing operation it will be aligned with the face of the pad 111 and will thus cooperate with the pad to press the side walls of

the mouth portion of the container 10, as shown in Fig. 9 of the drawings. The portion 129 of the sealing bar unit 128 is provided with a pin 136 to receive shackles 137. The opposite ends of the shackles 137 are connected to the lower ends of the piston rods 70 by pins 138. Thus, as the piston rods 70 reciprocate they will oscillate the sealing bar units 128 around the axis of shaft 123. It will be seen that when the shaft 123 rotates it will impart rotation to the gears 115 and 116. The rotation of the shaft 123 to the gears 115 and 116 is imparted through a helical spring 139 which is wound around the shaft 123 and is secured to the shaft at one end by a collar 140. The opposite end of the spring is secured to the boss of the lever arm 121, thus making it possible for a flexible drive to be established so that after the folding blades 103 and 110 have swung to their folding position, as shown in Fig. 9, the sealing bar structure 128 may continue to swing toward its sealing position and exert a desired pressure upon the seam to be formed without restriction from the folding mechanism. Attention is directed to the fact that at opposite ends of the blades 110 downwardly extending fingers 141 occur. These pass down along opposite sides of the mold, as indicated by dotted lines in Fig. 9.

In operation of the present invention flexible containers of the general character shown in Fig. 1 of the drawings are placed within the hopper 16 of the magazine unit A. They are then automatically withdrawn and shaped, as shown in Fig. 2 of the drawings, during which time they are deposited within molds 25 of a mold unit 24. The drive shaft 30 acts through a suitable intermittent drive mechanism to impart a step-by-step motion to the sprocket chains 23 and successively move a mold unit with a set of containers 10 to the filling hopper B and the spreading and stretching station C, and then in register with the sealing head 38 at the sealing station D. When the mold unit 24 is directly beneath the sealing head, as shown in Fig. 4 of the drawings, the cam 52 will be driven to lower the cam arm 48 and to thus act through the side arms 45 to lower the sealing head 38 into a position of rest upon the plate 31 of the mold unit. This position is particularly shown in Figs. 8 and 9 of the drawings. Here it will be seen that the packing strips 44 form a seal between the vertical walls of the sealing head 38 and the plate 31. It is to be understood that the pressure exerted against the packing strips 44 is sufficient to hold the sealing head vacuum-tight, so that when suction is exerted from a suitable suction pump and through the valves 77 and 78 the filled containers within the mold unit will be subjected to suction action so that a vacuum will be drawn in the containers and the molds within which they are placed. After the sealing head 38 has been positioned over the mold unit preparatory to a vacuumizing action, synchronized control means delivering air under pressure through the connection 68 to the manifold 67 will exert pressure on the pistons 69 tending to force the piston rods 70 downwardly. This will act through the sealing bar structure 128 connected with each piston to swing the sealing bar structure downwardly and to rotate the shaft 123 upon which it is mounted. Simultaneously a torque force will be imparted through the spring 139 to swing the lever arm 121 downwardly and to impart rotation to gear 115 through the shackle 120 and the pin 119. In view of the fact that the gears 115 and 116 are

in constant mesh, the gear 115 will rotate counter-clockwise, and the gear 116 will rotate clockwise. The gear segments 113 and 114 will then be rotated to swing the folding arms 98 and 99 around the axes of the shafts 100 and 101. The blade 103 of arm 99 will precede the blade 110 of the arm 98 so that the enlarged end portion of blade 110 will overlap the narrow end portion of blade 103. As these blades swing from the position shown in Fig. 9 to the position shown in Fig. 10 the portion 10a of the mouth of a container 10 will be folded together, and then the portion 112 of the blade 110 will fold a length 10b over the face 106 of the blade 103. In view of the length of the original portion 10a there will be a surplus amount of the package wall which would then fold upwardly and lie against the outer face of the pressure pad 111. As the piston 69 continues to move downwardly it may do so while rotating the shaft 123 and while permitting the lever arm 121 to stand stationary due to the provision for a lost motion between the screw 124 on the shaft 123 and the ends 126 and 127 of the slot 125 in the lever arm 121. Thus, while holding the arms 98 and 99 in their folding position the heat sealing bar 133 may be swung downwardly to bring its face 135 against the end portion of the container walls which now occur between the outer face of the pressure pad 111 and the face 135 of the sealing bar structure. Any desired pressure is then exerted directly through the piston rod 70 to the sealing bar structure 129 to force and hold the bar 133 against the side of the surplus end of the package. A clamping action will take place between the pressure pad 111 and the face 135 of the sealing bar, and since the sealing bar is being heated by the heating element 134 it will be recognized that since the inner surfaces of the walls of the package 10 are covered with thermoplastic material or the like a heat seal will be formed between these walls, and in actual practice this heat seal has proved to be vacuum-tight. It is to be understood that at a desired interval after the sealing head 38 has moved to a sealing position with relation to the plate 31 of the mold unit and before the time the sealing bar 133 is forcefully pressed toward the pad 111 to form the complete seal, the desired suction action takes place to create a condition of vacuum within the container 10 and around the container 10 within the mold 25 which it occupies. This operation is produced by first opening the valve 77 to permit a low negative pressure to be created by suction through the valve 77. After this has taken place the valve 77 may be closed and the valve 78 opened. This causes a high negative pressure to be created within the sealing head 38 and within and around the package. The heat sealing bar 133 is then forced firmly against the walls of the portion 10c of the container to produce the seal while the entire sealing head and mold unit are maintained under high negative pressure. When the heat sealing interval has been completed, valves 77 and 78 are both closed and valve 79 is opened to atmosphere. This permits air under atmospheric pressure to enter the sealing head 38 and to pass into the space between the sealed package and its mold 25, with the result that instantly the material within the package is compacted and the package is given permanent form and a shape agreeing with the configuration of the mold.

Attention is directed to the fact that when the folding arms 98 and 99 have moved to the position shown in Fig. 9 a point 110' on the blade 110 will assume a position agreeing with the faces 106 and

107 of the blade 103. This causes the length of the package walls, indicated at 10c, to be folded at an acute angle to the length of the package wall indicated at 10b, with the result that the suction action will evacuate air from within the package 10, but due to the fold will prevent small particles or dust from within the package 10 to be drawn between the two surfaces which are to be joined in the heat sealing operation. The valves, as previously explained, operate in sequence as controlled by the rotation of the cam shaft 80 and the cams 86, 91 and 96.

Attention is directed to the fact that since the sets of folding arms 98 and 99 which are provided to act upon the flexible containers in each of the molds will be given yieldable pressure as they move to their folded positions, and that the pressure bar 128 will thereafter impose a positive pressure upon the portion 10c of the container 10, this is due to the fact that a spring 139 is interposed between the positively rotated shaft 123 and the operating lever 121 for the gears 117 and 118. Thus, the folding arms 98 and 99 will fold down from the position shown in Fig. 8 to the position shown in Fig. 9, and thereafter while they are yieldably held the piston 69 provided for each of the molds 25 will continue to move downwardly, exerting pressure upon the sealing bar 128, so that a sealing action will take place between the pad 111 carried by the folding arm 98 and the face 135 of the sealing bar as the piston moves to the end of its power stroke. When this operation has been completed the springs 74 will retract the piston 69 and swing the sealing bar 128 from the position indicated in Fig. 9 to the position indicated in Fig. 8 and the folding arms 98 and 99 will swing from their commonly aligned position, as shown in Fig. 9, to the position shown in Fig. 8.

It will thus be seen that the method and means here disclosed insures that a filled flexible package will be subjected to suction action in a manner to prevent disturbance of the contents of the package, and that the mouth of the flexible package will be sealed vacuum-tight while an operation takes place to shape the package into fixed final form, all of which method is performed automatically by the apparatus here disclosed.

While I have shown the preferred form of apparatus by which my method of vacuum sealing flexible packages is performed, and have indicated the preferred steps of this method, it is to be understood that various changes in the combination, construction and arrangement of the parts of the apparatus and variations in the steps of the method may be made by those skilled in the art without departing from the spirit of the invention as claimed.

Having thus described my invention, what I claim and desire to secure by Letters Patent is:

Means for shaping and vacuum sealing filled flexible containers, which includes a mold within which a filled container is positioned and which mold agrees substantially with the final configuration of the sealed package desired, a sealing head adapted to assume a sealed position with relation to the mold and whereby a vacuum-tight chamber will be formed including said head and the mold, a pair of blades mounted within the head adapted to assume positions at opposite sides of the flexible unfilled portion of the container projecting above the mouth of the mold, pivotal mountings for said blades whereby the blades may swing to positions in a common plane normal to the top of the package being

sealed, the free edges of said blades engaging opposite side walls of the mouth of the flexible container, whereby said side walls will be moved together substantially along the median line of the package, said free blade edges overlapping when lying in the same plane to fold the free portion of said side walls substantially in a plane parallel to that assumed by the blades, a sealing bar adapted to move with relation to said blades when they have assumed a common plane to fold the outer end of the container walls in a reverse direction from the original fold and at an acute angle thereto, means for heating said sealing bar, means for moving said folding blades and the sealing bar in synchronism to fold the mouth of the package and thereafter seal the same by the exertion of heat and pressure by the sealing bar, and suction means associated with the vacuum-tight chamber whereby the interior and exterior

of the package will be subjected to suction action and after which the sealing bar will cooperate with a folding blade to heat seal the mouth of the package.
